UNITED STATES PATENT OFFICE.

FRED H. DANIELS, OF WORCESTER, MASSACHUSETTS.

ROD-ROLLING MILL.

No. 890,896.

Specification of Letters Patent.

Patented May 15, 1906.

Application filed August 1, 1902. Serial No. 117,978.

To all whom it may concern:

Be it known that I, FRED H. DANIELS, a citizen of the United States, residing at Worcester, county of Worcester, State of Massachusetts, have invented certain new and useful Improvements in Rod-Rolling Mills; and I do hereby declare the following to be a full, clear, and exact description of the invention, such as will enable others skilled in the art to which it appertains to make and use the same.

The invention relates to rod-rolling mills, and is herein illustrated and described in connection with a mill for rolling rods that are intended to be drawn into wire, though it is to be understood that this particular kind of mill is herein shown for purposes of illustration only, as the invention is equally applicable to mills for rolling rods for other purposes, as well as all sorts of elongated metal shapes.

My invention contemplates driving the finishing-rolls or other rolling-mill rolls by electric motors in the manner hereinafter described and claimed, and also a particular arrangement for connecting the motors to and driving the finishing-rolls.

The roughing and intermediate reducing-rolls are preferably geared to be driven by a common source of power, which is here shown as composed of two engines connected up to a single line-shaft, and the generator which supplies the motors is preferably driven by the same shaft, though this generator may be otherwise driven.

The invention is illustrated in the accompanying drawings, forming part of this specification, wherein—

Figure 1 shows in plan a "layout" of the entire mill, including the furnace and finishing-rolls and reels. Fig. 2 is an elevation of the finishing-rolls, showing one way of connecting the motors directly to the roll-spindles. Fig. 3 is an elevation of a modified arrangement for connecting the motors directly to the roll-spindles without the employment of pinion-housings. Fig. 4 shows a plan of the finishing-rolls and layout of Fig. 1 and illustrates the manner of wiring the motors to the generator.

Referring first to Fig. 1, *a* denotes a billet heating-furnace of any preferred type or construction. This form of furnace delivers short billets upon a conveyer *b*, composed of a series of rollers such as are commonly employed in rolling-mills. The conveyer deliv-

ers the billets to a series of roughing-rolls *c*, of which there may be any desired number. From the roughing-rolls the billets, now partially formed into rod, pass on to a set of intermediate reducing-rolls *d*, of which there may also be any number. The roughing and intermediate rolls are all geared up to a line-shaft *e*. The rolls of each set are driven at progressively-increasing speeds by means of miter or bevel gears of the proper size and pitch, as represented at *c'* and *d'* in Fig. 1, and the speed of the last of the intermediate roughing-rolls is considerably greater than that of the first of the reducing-rolls. From the intermediate reducing-rolls the rods pass in the ordinary manner to the finishing-rolls *i*. (Shown in Fig. 2.) As here shown, these rolls are of the double Belgian type; but they may be single Belgian, or what is known as "wholly continuous," or they may be of the Garrett or any other type, if preferred. Dotted lead lines in Figs. 1 and 5 show the course of the rods through these rolls, and the circles *k* denote the reels onto which the finished product is coiled.

Referring again to Fig. 1, *a'* *a''* denote a pair of engines. They are directly connected by what are known as "return-crank" to the line-shaft *e*, which, as before stated, is preferably continuous from the roughing to the intermediate reducing-rolls. These engines may be of any preferred type, but as here outlined they are compound engines with horizontal high-pressure cylinders *m* and vertical low-pressure cylinders *n*. Between the engines the shaft *z* is provided with an ordinary fly-wheel *o*, and an electric generator *b'* is also directly connected to and driven by the same shaft between the engines. The line-shaft is not extended beyond the intermediate reducing-rolls; but the finishing-rolls are driven by electric motors *p*, applied directly to their shafts or spindles, as shown in Figs. 2 and 4. These motors are supplied from and by the generator *b'*, and the motors are preferably of the type that are run in synchronism with their generator.

No particular description of the motors or generator or of the system of wiring is required; but an ordinary arrangement is shown in Fig. 4, where there are two motors for each pass, one being on the spindle of the upper roll and the other on the corresponding spindle of the lower roll. Any number of pairs of rolls may be employed. There are eight pairs shown in this double Belgian ar-

angement, four pairs on each side of the rod x coming from the intermediate reducing-rolls, and sixteen motors are therefore employed to drive them. The generator is represented in this figure as in immediate proximity to the rolls. This is only done for clearness of illustration, for, as represented in Fig. 1, it is located between the engines $a' a'$, and, as a matter of fact, it may be located at any more remote point.

All the motors are wired direct from a single generator, as indicated in the fourth figure, and should be driven to give the proper speed to take care of the elongation in the rod. They should also be provided with the usual switches and controlling devices for throwing the rolls into and out of operation, as desired, so that any pair or pairs may be discontinued should occasion require.

The mill herein shown is planned for rolling only one rod at a time; but it will be understood that there may be any number of furnaces and any number of pairs of rolls in either the roughing, intermediate, or finishing set, and that any number of rods may be rolled simultaneously.

The generator is essentially of the alternating type, and is here shown as a three-phase generator connected up in parallel with the several individual motors which are properly wired to revolve in the direction of the arrows in Fig. 4, so as to give the rolls the proper direction.

The motors illustrated are of the synchronous type; but the invention contemplates the driving of the rolls by any sort of electric motors that would give a constant speed to the rolls under the conditions existing in a rolling-mill.

In Fig. 3, what is known as a "three-high" Garrett arrangement of the finishing-rolls is shown. In this figure, a^3 denotes the rolls, and b^3 the roll-housings. The spindles of the top rolls are connected up in line, and the rolls are journaled directly in their housings, as shown, and driven without the employment of the pinion-housings heretofore considered necessary. The spindles of the lower and intermediate rolls are connected up, and the rolls are mounted in their housings in precisely the same way.

At each end of the train of rolls there is an electric motor $m m'$, and both these motors are wired to the single generator h^1 , as already described. The motor m is constructed with two armatures $m^1 m^2$, corresponding to the spindles of the top and bottom rolls to which they are directly connected or of which they form an extension through the motor.

The motor m' at the opposite end of the train of rolls has a single armature m^4 and which is connected to the line of spindles of the intermediate rolls in the way just described in connection with the other motor. The wiring of the motors is such as to give rotation in

the direction indicated by the arrows. Both motors should have the same number of revolutions per minute, and the motor m' should have double the horse-power of the motor m , for the obvious reason that the intermediate 7 line of rolls which are driven by it do double duty in connection with alternate passes of the train:

The construction and operation being as thus described, it will be understood that as 75 here planned the entire mill is driven from one unit, and that any fluctuation in speed will affect each stage correspondingly. The arrangement dispenses with all pinions, gears, belts, and shafting beyond the intermediate 80 rolls and insures a noiseless running of the finishing part of the mill and gives the whole a continuous and uniform load. It will also be understood that it is possible to vary the speed, and consequently the capacity of the 85 whole plant, by simply adjusting the speed of the unit, and the relative speed between the several parts of the mill will always remain constant.

The generator might be driven by a separate engine or by water or other power, if desired, and in some cases the roughing-rolls need not be driven from the same unit as the others; but on account of the loop between the reducing and the finishing rolls I prefer in any event to have the generator driven by the same engine that drives the intermediate rolls. It is not essential that the roughing and intermediate rolls be driven from one line of shafting by bevel-gearing. They may, if preferred, be driven by belts, ropes, or spur-gearing.

The invention is not intended to be limited to the application of synchronous electric motors to the finishing-rolls only, as obviously any of the rolls in a mill may be driven in this way.

Having thus described my invention, what I claim is—

1. In a rod-rolling mill, the combination of 110 a plurality of coöperating rolls, an electric generator, and motors applied directly to the spindles upon which said rolls are mounted, said motors being operatively connected to said generator.

2. In a rod-rolling mill, the combination of 115 a plurality of coöperating rolls, an alternating-electric-current generator, and an electric motor connected thereto and corresponding approximately to the speed of said generator, the armature of said motor being an extension of the spindle of one of said rolls.

3. In a rod-rolling mill, the combination of 120 a plurality of coöperating rolls with an electric motor applied directly to the spindle of each of said rolls and a common source of electric power connected to all of said motors.

4. In a rod-rolling mill, the combination of 125 reducing-rolls, an engine for driving said rolls, finishing-rolls, an electric generator, 130

and a motor operated by said generator for driving the finishing-rolls, said generator being operated by the engine that drives the reducing-rolls.

5. In a rod-rolling mill, the combination of roughing-rolls, and intermediate reducing-rolls, with a line-shaft to which both sets of rolls are geared, a pair of engines connected to drive said shaft, a set of finishing-rolls, an electric generator driven by the line-shaft, and a motor operated by said generator for driving the finishing-rolls.

6. In a rod-rolling mill, the combination of a set or train of three-high rolls, with electric motors located at opposite ends of the rolls, the top and bottom rolls being driven by one motor, and the intermediate rolls being driven by the other motor.

7. In a rod-rolling mill, the combination of a set or train of three-high rolls, with electric motors located at opposite ends of the rolls, the rolls in the top and bottom sets having their spindles in line with one another, and the spindles of said top and bottom sets being connected to and driven directly by the motor at one end of the rolls, and the spindles of the intermediate set being connected to and driven directly by the motor at the other end of the rolls.

In testimony whereof I affix my signature in presence of two witnesses.

FRED H. DANIELS.
